UNITED STATES PATENT OFFICE.

THOMAS H. GRANT, OF ROSEVILLE, CALIFORNIA.

DESIGN FOR A SIGNAL CASING FOR MOTOR VEHICLES.

Application filed March 9, 1926. Serial No. 16,849. Term of patent 3½ years.

To all whom it may concern:

Be it known that I, THOMAS H. GRANT, a citizen of the United States, residing at Roseville, in the county of Placer and State of California, have invented a new, original, and ornamental Design for a Signal Casing for Motor Vehicles, of which the following is a specification, reference being had to the accompanying drawing, forming part thereof, and in which—

Fig. 1 is a front elevation of a signal casing for motor vehicles, showing my new design, and

Fig. 2 is an end view of the casing.

I claim:

The ornamental design for a signal casing for motor vehicles as shown.

THOMAS H. GRANT.
